W. C. Lord

Attorney.

UNITED STATES PATENT OFFICE.

HYMAN LEWINSON, OF ERIE, PENNSYLVANIA.

SELF-FILLING FOUNTAIN-PEN.

1,392,838.

Specification of Letters Patent. Patented Oct. 4, 1921.

Application filed February 21, 1921. Serial No. 446,756.

To all whom it may concern:

Be it known that I, HYMAN LEWINSON, a citizen of the United States, residing at Erie, in the county of Erie and State of Pennsylvania, have invented new and useful Improvements in Self-Filling Fountain-Pens, of which the following is a specification.

This pen is designed to afford means for filling the barrel by the action of a valve plunger.

The invention is illustrated in the accompanying drawings as follows:—

Figure 1 shows a central section of the pen with the parts in position for use.

Fig. 2 an elevation, partly in section, showing the parts in the position which they assume in filling.

Fig. 3 a plan view of the plunger.

20 1 marks the barrel, 2 the closing plug at the bottom of the barrel, 3 the pen, and 4 the feeding opening leading to the pen.

A plunger 5 is mounted in the barrel surrounded with the yielding ring 6 to assure a tight joint. The plunger is actuated by a stem 7 which extends through the top of the barrel. A valve 8 is formed on the lower end of the plunger and operates on a valve seat 9 to open and close a passage 30 10 through the plunger. The stem is provided with a pin 11 which is adapted to enter a key-hole slot 12 and to turn in a socket 13 so as to lock the stem with the plunger with the valve 8 open.

35 The upper end of the barrel is screw-threaded. A valve plate 15 is screwed into this screw-threaded opening provided with a valve 16 on which a valve 17 operates. The valve has a frictional engagement with the stem 7 so that as the stem is pulled outwardly the valve is opened and when the stem is pulled inwardly the valve is closed.

A closure plate 18 is screwed into the end of the barrel. This has a vent-opening 45 20. The stem extends through the plate 18 and is provided with a cap 19 by means of which the stem may be conveniently operated and which when the pen is in position for use finishes the top end of the barrel.

50 The usual guard cap 21 is provided which is slipped over the lower end of the barrel when the pen is not in use and over the top of the barrel when the pen is in use.

In order that the ink may be readily expelled from the barrel when desired I prefer to provide a cam 22 above the plunger

which will engage the pin 11 if the stem is turned when the valve is seated. This will lock the valve on its seat and the plunger will then move with the stem and ink 60 may be expelled or drawn in as desired so that the pen may be thoroughly cleaned.

What I claim as new is:—

1. In a self-filling pen, the combination of a barrel having a feeding opening in the bottom; a plunger in the barrel; an axially moving valve in the plunger; a stem acting on the valve to close the valve as the plunger is withdrawn and to open the valve as the plunger is advanced; and means for detachably locking the stem with the plunger with the valve in open position. 65

2. In a self-filling pen, the combination of a barrel having a feeding opening in the bottom thereof; a plunger in the barrel, the plunger having an opening therethrough with a locking slot therein; a valve acting on the plunger to close the opening; a stem acting on the valve to close the opening in the plunger as the plunger is withdrawn 70 75 and to open the same as the plunger is advanced; and a shoulder on the stem operating in the locking slot to detachably connect the plunger with the stem.

3. In a self-filling pen, the combination of a barrel having a feeding opening at the bottom; a valve plunger in the barrel; a valve plate at the top of the barrel; a valve operating on the plate; and a stem extending from the plunger and actuating the valve to 80 85 open the same as the plunger is withdrawn and to close the same as the plunger is advanced.

4. In a self-filling pen, the combination of a barrel having a feeding opening at the bottom; a valve plunger in the barrel; a valve plate at the top of the barrel; a valve operating on the plate; a stem extending from the plunger and actuating the valve to open the same as the plunger is withdrawn 90 95 and to close the same as the plunger is advanced; and a vented closure cap above the valve plate.

5. In a self-filling pen, the combination of a barrel having a feeding opening at the bottom; a valve plunger in the barrel; a valve plate in the top of the barrel; a valve operating on the plate; a stem extending through the valve and connected with the plunger, said stem frictionally engaging the valve to open the valve as the plunger is retracted and to close the valve as the plun- 100 105 110

ger is advanced; and a vented closure at the top of the barrel.

6. In a self-filling pen, the combination of a barrel having a feeding opening in the bottom; a plunger in the barrel; an axially moving valve in the plunger; a stem acting on the valve; and means actuated by the stem for locking the valve in closed position.

10 7. In a self-filling pen, the combination

of a barrel having a feeding opening in the bottom; a plunger in the barrel; an axially moving valve in the plunger; a stem acting on the valve; and means actuated by the stem for locking the valve in closed or open 15 position.

In testimony whereof I have hereunto set my hand.

HYMAN LEWINSON.
